OFF-PEAK WATER HEATING SYSTEM

Arthur E. Julian, Chicago, Ill., and Clark M. Osterheld, Stoughton, Wis., assignors to McGraw Electric Company, Elgin, Ill., a corporation of Delaware

Application October 12, 1940, Serial No. 360,888

11 Claims. (Cl. 219—39)

Our invention relates to water heating systems and particularly to off-peak water heating systems.

An object of our invention is to provide relatively simple means for ensuring heating of water in a hot water tank during the off-peak period, means being included in said system to cause prolongation of the heating in case the tank contains less than a predetermined amount of hot water at the end of an off-peak period.

Another object of our invention is to provide means whereby continuation of heating of the water in a hot water tank beyond the end of an off-peak period is effected by thermal control means, in case the tank contains less than a predetermined amount of hot water at the end of an off-peak period.

Another object of our invention is to provide a water heating system wherein the heater will be deenergized during an off-peak period after having been energized for some time, in case all of the water in the tank has been heated to a given temperature and which will cause reenergization of the heater during an off-peak period in case of the withdrawal of appreciable quantities of hot water from the tank during that period.

Other objects of our invention will either be apparent from a description of several forms of systems embodying our invention or will be pointed out in the course of such description and set forth in the appended claims.

In the drawings,

Figure 1 illustrates our system as applied to a domestic hot water tank, which latter is shown in vertical section,

Fig. 2 shows a modified form of system embodying our invention, and

Fig. 3 shows a still further modification of electric water heating system embodying our invention.

Referring first to Fig. 1 of the drawings, we have there illustrated generally only a timing device 11 comprising a continuously operative synchronous motor 13 electrically connected to supply circuit leads 15 and 17. A worm gear 19 is mounted on the motor shaft and engages a worm wheel 21 which latter is mounted on a suitable shaft 23. The shaft 23 has also mounted thereon a cam disc 25 which has two different outer peripheral radii. The off-peak period of any day of twenty-four hours corresponds to a part of the periphery of cam disc 25 which has a larger radius and which is designated by 27 in this figure of the drawings. It is to be under-

stood that while we have illustrated a particular peripheral length of portion 27 as being of substantially eight hours in duration, our invention is not limited thereto but it is to be understood that any desired length of off-peak portion 27 of the cam disc 25 may be provided in accordance with the ideas of the engineers operating the utility supplying the electric current for energizing this system. If it is assumed that the duration of an off-peak period is substantially eight hours, it may be further assumed that the cam disc 25 is shown in the position which it will occupy at 10 o'clock in the evening so that the off-peak period may be considered to end substantially at 6 o'clock in the morning. It is further to be understood that the cam disc may be adjustably mounted on the shaft 23 so that the off-peak period may be started at any time desired by the operating company, may extend for any desired duration and may end at any time desired. While we have shown the motor-driven continuously operative timer in outline only, it is to be understood that all such details of construction as are necessary to cause the device to operate in the desired manner are to be provided but since most of these are mechanical only and constitute no part of our invention, we have not deemed it necessary to illustrate and describe such elements.

We provide a hot water tank 29 having an inlet pipe 31 for cold water connected thereto at the bottom end thereof and an outlet pipe 33 for hot water connected thereto at the top thereof. The tank may be surrounded by a mass 35 of suitable heat insulating material and an outer metal casing 37 may also be provided, all in a manner well known in the art, as these details are shown for illustrative purposes only and constitute no part of our invention.

An electric heater 39 is shown generally only as being mounted in any suitable or desired manner against the outer surface of the lower part of tank 29 and may be positioned within a tunnel 41 and reference may here be made to co-pending application Serial No. 284,881, filed July 17, 1939, by Clark M. Osterheld, in which a clamp-on flexible heater is disclosed and claimed. We desire it, however, to be understood that our invention is not limited to the use of a heater of this particular kind and we have, therefore, shown the heater generally only. A mechanically actuatable main heater control switch 43 may include a relatively rigid contact arm 45 and a resilient contact arm 47 normally yieldingly biased out of engagement with arm 45

but moved into engagement therewith when rotation of the cam disc 25 causes a lug 48, of electric insulating material, on contact arm 47 to be engaged by the portion 27 which has a larger outer radius than the other part of cam disc 25. Arm 45 is connected by a conductor 49 to one terminal of the electric heater 39 while the other terminal of heater 39 is connected to a substantially rigid contact arm 51 of a thermally actuatable switch 53 which includes in addition to the 10 arm 51, a resilient contact arm 55 normally yieldingly biased into engagement with contact arm 51 but moved out of engagement therewith by an expansion rod 57 mounted in and supported by a tubular member 59 which is secured in 15 a water-tight manner to the tank 29 in a suitable opening in its wall so as to extend through one wall thereof into the tank to be surrounded by the water in the tank at that point. It will be noted that we have illustrated the heater 39 as being located near the bottom of the tank with the thermal switch 53 positioned above the heater but we desire it to be understood that the position of the thermal switch 53 is to be so selected that it will not open the circuit of the 25 heater 39 controlled thereby by moving contact arm 55 out of engagement with contact arm 51, until substantially all of the water in the tank 29 is hot. Contact arm 55 is connected by a conductor 61 to the supply circuit conductor 17. We desire it to be understood also that while we 30 have shown, generally only, a particular form of thermally actuatable switch responsive to the temperature of the water in the tank at a predetermined point therein, we do not desire to be 35 limited to such construction and that we may use any other type of thermally actuatable switch controlled by tank water temperature without going beyond the limits of our invention.

We provide an electromagnetic switch or contactor 63 including a coil 65, an electromagnetic armature core 67, a pair of fixed contact members 69 and a movable contact bridging member 71 connected with core member 67 to be moved thereby into contact with contact members 69 and to be held in engagement therewith as long as coil 65 is traversed by an electric current. A conductor 73 connects contact arm 51 to one terminal of the coil 65 of contactor 63 while the other terminal of coil 65 is electrically 50 connected to one of the fixed contact members 69 which contact member is connected by a conductor 75 to conductor 49. The other fixed contact member of contactor 63 is connected by a conductor 77 to supply circuit conductor 15 and 55 therefore also to contact arm 47 of the timer-controlled switch 43.

Let it be assumed that there is an appreciable amount of cold water in the bottom part of tank 29 at the start of an off-peak period, this amount being sufficient to surround the tubular member 59 with cold water so that contact arm 55 will be in engagement with contact 51. It is evident that when portion 27 of cam disc 25 has been moved by synchronous motor 13 into substantially the position shown in Fig. 1 of the drawings, it being understood that discs 21 and 25 are rotated in a clockwise direction, contact arm 47 will be moved into engagement with contact arm 45 and since contact arms 55 and 51 are in engagement with each other, heater 39 will be energized through a circuit starting with supply circuit conductor 15, passing through engaged arms 47, 45, conductor 49, heater 39, engaged arms 51 and 55 and then through conductor 61 to 75

the other supply circuit conductor 17. At the start of an off-peak period and coincident with engagement of arms 47 and 45 and the establishment of a flow of current as just above described, contactor 63 will be energized, the circuit being substantially as follows: From supply circuit conductor 15 through the engaged contact arms 47 and 45 of switch 63, a part of conductor 49, conductor 75 to fixed contact member 69, through coil 65, through conductor 73, through the engaged contact arms 51 and 55 and from there through conductor 61 to the second supply circuit conductor 17. It is to be noted that this is a contactor-energizing circuit to magnetize armature core 67 with resultant upward movement thereof and engagement of contact bridging member 71 with the two spaced fixed contact members 69. This, it will be noted, establishes a shunt circuit relatively to the timer-controlled switch 43 but this has no other effect upon the system at this time. A holding circuit for the coil 65 may be traced substantially as follows: From supply circuit conductor 15 through conductor 77, fixed contact members 69 and contact bridging member 71, coil 65, conductor 73, contact arms 55 and 51 and from there through conductor 61 to the other supply circuit conductor 17.

Let it be assumed that tank 29 was almost full of hot water at the start of an off-peak period but that energization of heater 39 was effected as has been hereinbefore described. Let it be assumed further that substantially all of the water in the tank was heated to a desired temperature within a few hours, so that temperature-responsive switch 53 caused disengagement of contact arm 55 from contact arm 51 sometime during an off-peak period, for example, at say 2:00 a. m. with resultant deenergization of the heater. The electromagnetic contactor 63 would also be opened because its holding circuit was interrupted by disengagement of the contact arm 55 from contact arm 51, but timer-controlled switch 43 would still remain in closed position. If, now, sudden withdrawals of hot water from the tank 45 occur say at 3:00 a. m., that is, before the end of that off-peak period, to such an extent that tubular member 59 is surrounded by cold water, the hereinbefore described circuit through heating element 39 would be reestablished and at the same time contactor 63 would be moved to the position where contact bridging member 71 would be in engagement with fixed contact members 69. Let it be further assumed that a relatively large amount of hot water was withdrawn so that the energized heater 39 would not provide enough heat during the remaining part of the off-peak period and an appreciable portion of the water in the tank was still cold at the end 60 of the off-peak period, disengagement of contact arms 47 and 45 from each other at the end of that off-peak period because of the movement of portion 27 out from under the lug 48 on arm 47 would not cause deenergization of the heater since its heating circuit now is substantially as follows: From supply circuit conductor 15 through conductor 77, cooperating contact members 69 and 71, conductors 75 and 49, through heater 39, through the engaged contact arms 51 and 55 and through conductor 61 to the other supply circuit conductor 17. It is further evident that energization of the heater beyond the end of the off-peak period will continue for as long as the tubular member 59 of the thermal switch 53 is surrounded by cold water and it may

be here pointed out that such energization may continue during a shorter or a longer portion of the following part of the day after the end of an off-peak period, in case additional withdrawals of hot water take place before all of the water in the tank is hot. It is noted here that while reenergization of the heater 39 will occur during an off-peak period in case of first a de-energization of the heater because all of the water in the tank is hot and in case of withdrawal of hot water from the tank, but this is not the case after the end of an off-peak period. It may further be pointed out that in this modification of an off-peak water heating system embodying our invention, a prolongation of the energization of the electric heater is effected in case the tank is not full of hot water.

Referring now to Fig. 2 of the drawings, we have there illustrated a modified system embodying our invention which differs somewhat from that shown in Fig. 1 of the drawings, more particularly that prolongation of the energization of the electric heater 39 beyond the end of an off-peak period will be effected in case the amount of hot water in the tank at the end of an off-peak period is approximately less than half the total amount of water in the tank. When a water heating system of the kind embodying our invention is applied to an ordinary domestic hot water tank whose height is several times that of its diameter, the hot water will be located in the upper part of the tank and any cold water in the tank will be found in the lower part thereof with a more or less well defined line of demarcation between the hot and the cold water. The description to be given hereinafter of the system shown in Fig. 2, as well as that shown in Fig. 3, refers more particularly to a tank approximately half full of hot water, but we desire it to be understood that this is a general statement and that, within the scope of our invention, we may so arrange auxiliary thermally controlled elements that prolongation of the heating of the water beyond the end of an off-peak period will occur after the tank is less than one-third full of hot water or is less than two-thirds full of hot water at the end of an off-peak period.

Those parts of the system illustrated in Fig. 2 of the drawings which are the same as those in the system shown in Fig. 1 of the drawings are provided with the same reference numerals and we may point out that we provide a continuously operative timer 11, a tank 29, a tank heater 39, a main thermally actuatable heater control switch 53 positioned near the bottom of the tank, an electromagnetic heater control switch 63, but in addition thereto we provide an auxiliary thermally actuatable switch 79 which includes a tubular member 81, an expansion rod 83 therein engaging, when expanded, a resilient contact arm 85 which is normally yieldingly biased into engagement with a relatively rigid contact arm 87. In general, this auxiliary switch is substantially the same as the main thermal switch 53 and the same comments as to the use by us of a different form of thermally controlled switch apply here also. We have shown the thermally actuatable switch 79 as located approximately at half the height of the tank but do not desire to be limited thereto as it may be located either higher up or lower down in the tank and where we have used the words "half full of water" or similar words, it is to be understood that this can be changed to correspond to the ratio of hot or cold water in the tank corresponding to the fixed po-

70 sition of the auxiliary thermally actuatable switch 79. Contact arm 51 is connected by a conductor 89 to contact arm 87 and contact arm 85 is connected through a conductor 91 to one terminal of coil 65 of contactor 63, the other connections of the contactor being as hereinbefore described.

Let it be assumed that timer-controlled switch 43 is in the position shown in Fig. 2 of the drawings, having been moved into this position by engagement with portion 27 of cam disc 25 at, say, 10:00 p. m. In case of the presence of an appreciable amount of cold water in the tank sufficient to surround tubular member 59 at the start of an off-peak period, contact arms 55 and 51 will be in engagement with each other and an energizing circuit through heater 39 will be established, it being noted that timer-controlled switch 43 and tank water temperature-controlled switch 53 are connected in series circuit relation 20 relatively to each other. Let it be assumed that there was only a relatively small amount of cold water in the tank at the start of an off-peak period and that all of the water in the tank became hot on or before 2:00 a. m. when switch 53 would interrupt the energizing circuit through heater 39 to cause deenergization thereof. If withdrawals of hot water were effected at say 25 3 or 4 o'clock in the morning, that is, during the off-peak period, switch 53 would again close, provided that an appreciable amount of hot water was withdrawn, with resultant reenergization of heater 39.

Let it be assumed that withdrawal of hot water from the tank was effected to such an extent that the tank was less than two-thirds full of hot water, less than one-half full of hot water, or less than one-third full of hot water in accordance with the position of the auxiliary thermal switch so that the auxiliary thermally actuatable switch 79 was surrounded by cold water just before the end of an off-peak period. Contact arms 85 and 87 would then be in engagement with each other and would close an energizing circuit through coil 65 of contactor 63 substantially as follows: From supply circuit conductor 15 through engaged contact arms 47 and 45, through conductors 49 and 75 to contact member 69, through coil 65, conductor 91, through engaged contact arms 85 and 87 of thermal switch 79, through conductor 89 and engaged contact arms 51 and 55 of the main thermal switch 53 and through conductor 61 to the other supply circuit conductor 17. A holding circuit for coil 65 is also established, extending substantially as follows: From supply circuit conductor 15 through conductor 77, through contact members 69 and 71, coil 65, conductor 91, engaged contact members 85 and 87, conductor 89, engaged contact arms 51 and 55 and through conductor 61 to the other supply circuit 17.

If, now, this condition was brought into existence just before the close of an off-peak period, that is, withdrawals of hot water from the tank occur to such a degree that the upper auxiliary thermal switch 79 was subjected to cold water, and if this continued to the end of the off-peak period when contact arms 47 and 45 moved out of engagement with each other, the electromagnetic contactor 63 would remain in heater circuit closing position, this circuit extending substantially as follows: From supply circuit conductor 15 through conductor 77, through engaged contact members 69 and 71, through conductors 75 and 49, heater 39, engaged contact members 51 and 55 and from there

through conductor 61 to the supply circuit conductor 17. It is obvious that when the auxiliary thermal switch 79 is closed because it is immersed in cold water, the lower or main thermally actuatable switch 53 is also closed because it also is immersed in cold water. It is further evident that under these conditions energization of the heater 39 will continue until the tank is at least one-third, one-half, or two-thirds full of hot water in accordance with the position of the auxiliary switch when thermal switch 79 will be subjected to hot water with the result of causing disengagement of contact arm 85 from contact arm 81, interruption of the above described holding circuit of contactor 63 and de-energization of the heater 39. Whereas in the system shown in Fig. 1 of the drawings prolongation of the heating effect of the energized heater 39 on the water in the tank continues until the tank is full of hot water, our system shown in Fig. 2 of the drawings is effective to continue energization of the electric heater in case the tank is less than one-half full of hot water at the end of an off-peak period or less than some other predetermined portion as described hereinbefore.

Referring now to Fig. 3 of the drawings, we have there illustrated a still further modification of an off-peak water heating system embodying our invention in which a series type of electromagnetic contactor coil may be used. Such parts of the system as are the same are provided with the same reference numerals as in Figs. 1 and 2 of the drawings. In this system the relatively rigid contact arm 45 is connected through a conductor 93 to one of the fixed contact members 95 of an electromagnetic contactor 97 which includes in addition to a coil 99, a magnetizable core member 101 which has connected thereto a contact bridging member 103 adapted to be moved into engagement with contact members 95 upon energization of coil 99. One terminal of coil 99 is connected to that fixed contact member 96 which has conductor 93 connected thereto while the other terminal of coil 99 is connected by a conductor 105 to contact arm 55 of the main thermally actuatable switch 53. An auxiliary thermally actuatable switch 107 includes a tubular member 109, an expansion rod 111 therein adapted to engage and move a resilient contact arm 113 normally yieldingly biased into engagement with a relatively rigid contact arm 115. Contact arm 113 is connected by a conductor 117 with the other fixed contact member 95 of contactor 97 while contact arm 115 is connected by a conductor 119 to contact arm 47 of the timer controlled switch 43.

Let it be assumed that the main thermally actuatable switch 53 is subjected to the temperature of cold water in the lower part of the tank so that contact arms 55 and 51 are in engagement with each other at the start of an off-peak period when contact arm 47 is moved into engagement with contact arm 45, as shown in Fig. 3 of the drawings. An energizing circuit through the heater will be established as follows: From supply circuit conductor 15 through engaged contact arms 47 and 45, through conductor 93 and through coil 99, conductor 105, through engaged contact arms 55 and 51 to the heater 39 and from there through conductor 61 to the other supply circuit conductor 17. This will cause energization of heater 39 and 75

attendant heating of the cold water in the lower part of the tank.

The energized coil 99, traversed by the current flowing through heater 39 as above described, causes energization of armature core 101 with resultant upward movement thereof and engagement of contact bridging member 103 with contact members 95. This energized condition of the coil 99 will continue for as long as current flows through heater 39. In case all of the water in the tank is heated to a temperature sufficient to cause disengagement of contact arms 55 and 51, deenergization of the heater 39 is effected, should all of the water in the tank be heated before the end of an off-peak period. In case hot water is thereafter withdrawn from the tank, to an appreciable extent, the main thermal switch 53 may be moved to circuit closing position and the heater 39 will be reenergized.

If it be assumed that the amount of hot water withdrawn during the latter part of an off-peak period was so much that the auxiliary thermally actuatable switch 107 was subjected to cold water, prolongation of the energization of heater 39 would result through a circuit substantially as follows: From supply circuit conductor 15 through conductor 119, through engaged contact arms 115 and 113, through conductor 117, through engaged contact members 95 and 103, through coil 99, through conductor 105, through engaged contact arms 55 and 51, through heater 39 and through conductor 61 to the other supply circuit conductor 17. This energization of heater 39 would continue until the amount of hot water in the tank would be sufficient to immerse tubular member 109 of switch 107 in hot water, when contact arm 113 would be moved out of engagement with contact arm 115 with resultant interruption of the energizing circuit through heater 39. The same comments as regards the position which auxiliary thermally actuatable switch 107 may occupy made hereinbefore with regard to auxiliary switch 79 apply also to switch 107.

It is therefore evident that the water heating system embodying our invention as herein described in its several modifications provides for start of the energization of the electric heater of a hot water tank at the start of an off-peak period. It provides further thermally controlled means responsive to the temperature of a predetermined part of water in the tank or to the temperature of water in a desired point in the tank to effect prolongation of energization of the tank heater beyond the end of an off-peak period, this energization continuing until a predetermined part of the water in the tank, which may be either the whole contents or a desired part thereof, has been heated to a predetermined temperature which we have designated broadly as "hot."

While we have illustrated and described certain embodiments of our invention now preferred by us, we do not desire to be limited thereto and any further modifications clearly coming within the scope of the appended claims are to be considered as being covered thereby.

We claim as our invention:

1. An off-peak water heating system for a hot water tank having a single electric heater adjacent to the bottom of the tank, comprising a continuously operative timing means, a heater control switch adapted to be held closed by said timing means during an off-peak period, a thermal

heater control switch in series circuit with said timer-controlled switch subject to water temperature and maintained in closed position until the tank is full of hot water and auxiliary heater control switching means controlled jointly by the timing means and by thermal means subject to the temperature of the water in the tank to cause continuation of the energization of the heater beyond the end of the off-peak period in case the thermal means subject to the temperature of the water in the tank is subject to relatively cold water at the end of an off-peak period.

2. An off-peak water heating system for a hot water tank having a single electric heater adjacent to the bottom of the tank and comprising a continuously operative timing means and a plurality of electrically connected switching means controlled separately and jointly by the timing means and by the tank water temperature for causing energization of the heater at the start of an off-peak period in case the tank contains an appreciable amount of cold water at the start of an off-peak period, for causing continuation of the energization of the heater beyond the end of the off-peak period in case the tank contains less than a predetermined amount of hot water at the end of an off-peak period and for causing deenergization of the heater when the tank contains more than said predetermined amount of hot water.

3. An off-peak water heating system for a hot water tank having a single electric heater adjacent to the bottom of the tank and comprising a continuously operative timing means and a plurality of electrically connected switching means controlled separately and jointly by the timing means and by the tank water temperature for causing energization of the heater at the start of an off-peak period in case the tank contains an appreciable amount of cold water at the start of an off-peak period, for causing continuation of the energization of the heater beyond the end of the off-peak period in case the tank contains less than a predetermined amount of hot water at the end of an off-peak period, for causing deenergization of the heater during an off-peak period when the tank contains more than said predetermined amount of hot water and for causing reenergization of the heater during the off-peak period in case withdrawals of hot water from the tank reduce the amount of hot water in the tank to less than said predetermined amount.

4. An off-peak water heating system for a hot water tank comprising an electric heater, a control switch therefor, a continuously operative timer for causing closing of said control switch at the beginning of an off-peak period and holding it closed for a predetermined length of off-peak time, and thermally and electromagnetically controlled switching means to cause continuance of the energization of said heater beyond the opening of the timer-controlled switch until the temperature of substantially all of the water in the tank is at a predetermined value.

5. An off-peak water heating system for a hot water tank comprising an electric heater, a control switch therefor, a continuously operative timing means for causing closure of said switch at the beginning of an off-peak period and for holding it closed for a predetermined length of off-peak time, a normally closed thermally-controlled switch connected in series circuit with said first named switch for causing deenergization of the heater when substantially all of the

water in the tank has been heated to a given temperature and an electromagnetic switch connected in parallel-circuit with said timer-controlled switch to cause continuation of heating of the water in the tank by said heater after opening of the timer-controlled switch at the end of the off-peak period until substantially all of the water in the tank has been heated to said given temperature.

10 6. An off-peak water heating system for a hot water tank comprising an electric heater, a control switch for said heater, a continuously operative timing means for causing closing of said switch at the beginning of an off-peak period and for holding it closed for a predetermined length of off-peak time, a thermally-controlled switch for said heater subject to the temperature of water in the tank, an electromagnetically-controlled switch connected in parallel-circuit relation with said timer-controlled switch, circuit connections between all of said switches to cause closure of said electromagnetically-controlled switch on closure of said timer-controlled switch and to cause opening of the thermally-controlled switch and of the electromagnetically-controlled switch when the temperature of all of the water in the tank is above a predetermined value irrespective of the operative position of the timer-controlled switch.

15 7. An off-peak water heating system for a hot water tank having a single electric heater located adjacent to the lower end of the tank and comprising a continuously operative timing means, a heater control switch adapted to be held in heater-energizing position by said timing means during an off-peak period, a thermally-actuable heater control switch cooperating with said timer-controlled switch to effect energization of the heater at the start of an off-peak period in case of the presence of an appreciable quantity of cold water in the tank at the start of an off-peak period and thermally-controlled switching means for ensuring continuation of the energization of the heater beyond the end of an off-peak period in case of the presence of a predetermined quantity of cold water in the tank at the time of movement of the timer-controlled switch to heater-deenergizing position.

20 8. An off-peak water heating system for a hot water tank having a single electric heater adjacent to the bottom of the tank and comprising a continuously operative timing means, a heater control switch adapted to be held in heater-energizing position by said timing means during an off-peak period, a thermally actuable heater control switch cooperating with said timer-controlled switch to effect energization of the heater at the start of an off-peak period in case of the presence of an appreciable quantity of cold water in the tank at the start of an off-peak period and a thermally-controlled electromagnetic switch electrically connected in shunt circuit relation with said timer-controlled switch for continuing the energization of the heater beyond the end of the off-peak period in case of the presence of a predetermined quantity of cold water in the tank at the end of an off-peak period, said energization continuing until the tank contains appreciably less than said predetermined quantity of cold water.

25 9. An off-peak water heating system for a hot water tank having a single electric heater located near the lower end of the tank, comprising a supply circuit for said heater, a continuously operative timer, means including an electromag-

netic switch in said circuit for controlling the energization of said heater, a plurality of switches controlled respectively by tank water temperature and by said timer and electric connections between said plurality of switches, the coil of the electromagnetic switch and the supply circuit ahead of said timer controlled switch for causing energization of said heater at the start of an off-peak period in case said switch controlled by tank water temperature is subject to relatively cold water and to continue energization of the heater beyond the end of an off-peak period in case said switch controlled by tank water temperature is subject to relatively cold water at the end of an off-peak period.

10. An off-peak water heating system for a hot water tank having a single electric heater located adjacent the bottom end of the tank, comprising a supply circuit for said heater, a continuously operative timing means, a heater control switch in said circuit adapted to be held closed by said timing means during an off-peak period to cause energization of said heater, an electromagnetic heater control switch, a thermally actuatable switch subject to tank water temperature and electric connections between said thermally actuatable switch, the coil of said electromagnetic switch and the supply circuit ahead of said heater control switch actuated by said timing means for causing continuation of the 30 energization of said heater beyond the end of an off-peak period in case the thermally actuatable switch is subject to the temperature of relatively cold water at the end of an off-peak period.

11. An off-peak water heating system for a hot water tank having a single electric heater located near the lower end of the tank, comprising a supply circuit for said heater, a continuously operative timer, means including an electromagnetic switch in said circuit for controlling the energization of said heater, a plurality of switches controlled respectively by tank water temperature and by said timer and electric connections between said plurality of switches, the coil of the electromagnetic switch and the supply circuit ahead of said timer controlled switch for causing energization of said heater at the start of an off-peak period in case said switch controlled by tank water temperature is subject to relatively cold water, for causing deenergization of the heater during an off-peak period when the switch controlled by tank water temperature is subject to relatively hot water, for causing reenergization of the heater during an off-peak period in case withdrawals of hot water from the tank cause the switch controlled by tank water temperature to be subject to relatively cold water and for causing continuation of the energization of the heater beyond the end of the off-peak period in case the switch controlled by tank water temperature is subject to relatively cold water at the end of an off-peak period.
